(57) **CLAIM**

The ornamental design for a bag foot, as shown and described.

DESCRIPTION

FIG. 1 is a top front perspective view of a bag foot;

FIG. 2 is a top plan view thereof; and

FIG. 3 is a bottom plan view thereof.

FIG. 4 is a front elevation view thereof;

FIG. 5 is a rear elevation view thereof;

FIG. 6 is a right side elevation view thereof; and,

FIG. 7 is a left side elevation view thereof.

The broken lines shown in the drawings depict portions of the bag foot that form no part of the claimed design.
